SPRING CUSHION

Gustave P. Johnson, Waukegan, Ill.

Application August 9, 1937, Serial No. 158,629

6 Claims. (Cl. 155—179)

The present invention relates to spring cushions intended primarily for chairs, although in its broader aspects the invention is also applicable to lounges, beds, cots, and other furniture. 5
Heretofore, the vertically disposed coil springs of the spring cushion seats in upholstered chairs have generally been supported on a fabric bottom composed of a plurality of strips of fabric webbing or of a single piece of webbing secured 10 to the frame of the chair. Where the chair has considerable use, this fabric webbing usually deteriorates more rapidly than the remainder of the chair structure, and has a tendency to tear loose from its points of attachment to the frame 15 or to tear at other points of localized strain, thereby permitting some of the springs to sag or become tilted in the spring assembly. Also, it is difficult to make a durable, lasting attachment of the lower ends of the coil springs to the webbing, and, in addition, the webbing is 20 unsanitary because of the inability to clean the upper surface thereof. Furthermore, in some instances, where the webbing is arranged in strips, the spring assembly or different rows of the 25 springs may have an objectionable tendency toward side sway.

The principal object of the present invention is to avoid these objections by providing an improved spring cushion characterized by a flexible metallic bottom preferably composed of a section 30 of wire netting on which the coil springs are mounted. This wire netting has an inherent resiliency, and still is not subject to deterioration and tearing.

Another object of the invention is to provide 35 such improved spring cushion in which the section of wire netting has resilient attachment to the supporting frame through the medium of springs which give an additional resiliency to the entire seat. The latter springs are preferably in the form of tension springs which can 40 be readily hooked between the netting and the frame. A full-floating construction can be had by interposing these tension springs between 45 both the front and rear edges of the netting and the frame, or a semi-floating construction can be had by interposing said springs between only one end of the netting and the frame. The entire cushion can be readily adjusted to accommodate 50 users of different weights, or to meet any individual desire on the part of the purchaser for a greater or lesser resiliency, by merely adding to or subtracting from the total number of tension springs connecting the wire netting to the frame, which operation can be readily per-

formed without disassembling the spring cushion.

Another object of the invention is to provide an improved spring cushion of this general type in which the wire netting is of such construction that the bottom convolutions of the vertically disposed coil springs can be "screwed" or threaded into the netting. This method of attaching the coil springs to the netting can be performed with such ease and facility that it is a great time-saving factor in the manufacture 5 of the cushion, and, in addition, such method establishes a fixed anchorage for the springs and affords a broad base support therefor.

The relatively large open mesh of the netting enables the upper surface thereof to be readily 15 cleaned with a brush.

Other objects and advantages of the invention will appear from the following detailed description of certain preferred embodiments thereof. In the accompanying drawings illustrating such 20 embodiments:

Figure 1 is a plan view of the spring cushion, the wire netting being illustrated diagrammatically;

Figure 2 is a longitudinal sectional view there- 25 of the cushion approximately on the plane of the line 2—2 of Figure 1;

Figure 3 is a fragmentary perspective view on a larger scale, showing the wire netting in detail 30 and illustrating the manner in which the vertically disposed coil springs are threaded into said netting;

Figure 4 is a fragmentary vertical sectional view through a modified construction;

Figure 5 is a detail sectional view of another 35 modified construction; and

Figure 6 is a fragmentary plan view of still another modified construction.

The spring cushion comprises a supporting frame which I have illustrated in the form of a 40 box frame 11 constituting the base of a chair, although I wish it to be understood that any other desired form of frame may be employed. The frame illustrated comprises the two side rails or boards 12, 12, and the front and back 45 rails or boards 13, 14. The corners may be reinforced by suitable corner braces 15, and the supporting legs or feet 16 may be provided with upwardly projecting extensions 16' rigidly secured in the corners between the side and end 50 rails. The side arms and the back of the chair are preferably constructed of separate pieces suitably secured to the side and back rails of the base, although they might be formed as extensions of these base rails.

The vertically extending coil springs 18 are preferably of the double cone type. The section of wire netting 19 constituting the flexible supporting bottom for these springs preferably has its length extending from front to back of the chair for support on the front and back rails 13 and 14. Although different types of netting may be employed, I preferably use netting of the chain link type in which the individual strands of wire 19a extend transversely of the length of the netting and are looped back and forth for linked connection with adjacent strands, such netting being illustrated only diagrammatically in Figure 1 but being illustrated in detail in Figure 3. Such type of netting has a substantial degree of resiliency or elasticity without deformation, particularly in the direction of its length. One of the features of my invention is the employment of chain link netting in which the mesh, thickness of wire, and interlooped relation of the strands are such that there is a substantial spacing between the upper and lower portions of the wire loops, and all so related that the lower convolutions 18' of the coil springs 18 can be readily screwed or threaded into the netting, as illustrated in Figure 3. That is to say, the mesh of the netting is of sufficient size, and the successive loops formed in each strand 19a are so proportioned and shaped, that the upper strand portions or loop portions 19b and the lower strand portions or loop portions 19c lie in separate horizontal planes which are spaced apart vertically a substantial distance, viz, at least equal to the thickness of the wire in the cushion springs 18. By virtue of this construction, the bottom convolution 18' of each cushion spring 18 can be rotated to pass freely in a substantially horizontal plane between the lower surfaces of the upper strand or loop portions 19b and the upper surfaces of the lower strand or loop portions 19c without requiring any laborious mechanical operation, such as bending, kinking or otherwise deforming either the spring convolutions or the strands of the netting. It should also be noted that because the cushion springs 18 are of the conical type, it follows that the lower convolutions 18' progressively decrease in diameter upwardly toward the intermediate or upper portion of each spring. Hence, by merely rotating the cushion spring within the netting, the progressively decreasing diameter of its bottom convolution exerts a contracting or tightening action on all of the strands 19a through which said convolution is threaded, which tightening action can easily be made very firm, if desired, thereby establishing a locked or clamped relation between the cushion spring and the netting, so that disengagement of the spring is prevented and, also, so that rattling or metal-to-metal sound is avoided as the load on the cushion spring is shifted or varied. By avoiding the necessity of kinking, bending or otherwise deforming either the spring convolutions or the strands of the netting, the operation of threading or rotating the spring convolutions into the netting can be quickly and easily performed, thereby minimizing the labor item of securing the springs to the flexible bottom; and, furthermore, by such method of attachment the springs are fixedly held against displacement and are given a broad base of supporting contact on the flexible bottom by reason of their engagement with a multiplicity of the strands 19a at a plurality of widely spaced points. The substantial degree of vertical spacing which exists between the plane of the upper portion 19b

of each strand loop and the plane of the adjacent lower portion 19c of the strand loop, gives a further advantage beyond the advantage of facilitating the threading of the lower spring convolutions 18' into the netting, namely, that of affording a considerable degree of rolling freedom between adjacent strands. That is to say, the side portions 19d—19d of each strand loop, which establish interconnection between adjacent strands, are shaped or bent on a curvature such that the inner radius of each such side loop portion is at least equal to or larger than the radius of the wire constituting the cushion springs 18. Hence, the contact between the cylindrical surfaces of these side loop portions 19d—19d is of relatively small area, normally approximating that of a point contact, and the side loop portions of each interconnected pair of loops can be rolled or rocked in either direction relatively to each other. Consequently, the netting can be freely warped or twisted into different planes without permanently stretching or distorting the netting. By thus enabling the netting to adapt itself more readily and more resiliently to a shifting or unevenly distributed load, the flexibility and comfort of the spring cushion is increased.

The above mentioned points of contact between the springs and the strands 19a are indicated in Figure 3 at a, b and c. It will be noted that it is the pressure exerted by the netting edgewise against the coil 18' at these points which determine the limit of the rotation of the spring during its insertion, and that these points of support between the spring and netting are necessarily closely adjacent the crossing points, at 19d, where the netting strands have their above-mentioned rolling or rocking freedom. At the other points the strand portions are by virtue of their spacing not held tightly to the spring. The entire netting is free to flex downwardly as the springs 27 yield, as indicated in Figure 4, without being materially restrained by the lower coils 18' of the several springs. This adds materially to the flexibility to the seat bottom, as will be readily apparent from Figure 4, for otherwise the flexibility of the netting would be limited to portions outside the spring bases, and from Figure 1 it will be seen that the spring bases occupy the major portion of the netting.

In the semi-floating construction illustrated in Figures 1 and 2, the front strand of the wire webbing 19 has its successive loops laced through holes 21 in an attaching bar 22, which is secured by nails or screws 23 to the front rail 13 of the frame. This laced attachment of the wire webbing to the bar 22 assures an equal distribution of the load transmitted from the webbing to the bar, and also prevents shifting of the loops of the end strand or distortion of this end strand.

The opposite edge of the wire netting has a stiffening rod 25 extending through the loops of the end strand, the extremities of this rod being bent rearwardly as indicated at 25' to prevent displacement of the rod. Hooked between this end of the netting and another attachment bar 22a are a plurality of helical tension springs 27, the latter being stretched slightly to impose a continuous tension on the netting. The attachment bar 22a can be a duplicate of the other attachment bar 22, being secured to the rear frame rail 14 by the nails or screws 23a and being provided with a plurality of closely spaced holes 21a in which the hook extremities at the rear ends of the tension springs are engaged, the hook extremities at the front ends of said springs 75

being engaged over the stiffening rod 25 at points within the loops of the netting.

6 The connections are established between the upper ends of the compression springs in any suitable manner, although I preferably employ the conventional cords 28, as illustrated. The ends of these cords are anchored to the side and end rails of the frame by the nails or brads 29. When the chair seat is to have a yieldable front 10 edge, the tie connections for the springs disposed along the front edge of the frame are so arranged that these springs are inclined forwardly in order to dispose their upper ends substantially even with the front edge of the frame. A conventional 15 pad secured over the upper ends of the compression springs 18 is indicated in dotted lines at 31, and the upholstering material which encloses the spring cushion is indicated in dotted lines at 32. An upper cushion, either removable or fixed, is 20 indicated in dotted lines at 33.

By virtue of the spring attachment of the wire netting to the supporting frame, it will be evident that the spring cushion will have the combined resiliency of the compression springs 18 and the 25 tension springs 27. The cushion can be readily adjusted to accommodate different weights or to have a greater or lesser degree of resiliency by adding or subtracting tension springs 27 between the stiffening rod 25 and attachment bar 22a, 30 two such additional springs being indicated in dotted lines in Figure 1. It is also possible to distribute the tension springs so as to concentrate a greater part of the tension either at the center or at the edges of the webbing; if such is 35 desired. The resilient attachment of the wire netting to the frame 11 through the medium of the tension springs 27 prevents the netting from being distorted or stretched out of shape by any sudden or abnormal load. The netting has sufficient transverse stiffness to prevent objectionable side sway. It will be observed that in the 40 preferred embodiment above described it is only the front and rear edges of the chain-link netting which have supported attachment to the main frame 11. Hence, the maximum tensile stresses 45 are along substantially parallel lines extending between the front and back edges of the section of netting, which means that these stresses are substantially at right angles to the direction of the transverse wire strands 19a which make up the netting. Therefore, in this preferred embodiment there are no strands in the netting extending 50 in the direction of maximum tensile stress. This is advantageous because strands extending 55 in the direction of maximum tensile stress resist with their full tensile strength any resiliency of the netting, and if such strands have loops formed therein these loops tend rather quickly to stretch out into a straight line so that the netting quickly 60 assumes a permanent sag. I have found that a greater degree of resiliency is obtained, with less likelihood of the netting assuming a permanent sag, when the side edges of this chain-link netting are left free of connection with the supporting frame 11, so that all of the load is sustained 65 in a direction substantially at right angles to the strands 19a, whereby the intermediate portion of the netting is left free to contract and expand laterally in its transverse dimension with change 70 of load. However, I also consider it to be within the scope of my invention to interpose relatively light tension springs between the side edges of the netting and the frame 11, so long as the major portion of the load is sustained in a direction 75 substantially at right angles to the individual

strands 19a. The relatively large radius of curvature of the interconnecting side loop portions 19d—19d, previously described, also augments the resiliency of the netting to stresses acting in a direction substantially at right angles to the general length of the individual strands. 5

My improved spring assembly may be disposed at any desired height relatively to the frame 11, to accommodate frames of different heights or to provide for different heights of the seat in the 10 chair. In Figure 4 I have illustrated the spring assembly lowered the depth of the frame. For such arrangement, the attachment bars 22 and 22a are merely transposed from the top edges 15 to the bottom edges of the front and rear frame rails 13, 14. In Figure 5 I have illustrated the spring assembly as being attached to the frame 11 at a point intermediate the top and bottom edges of the frame. In this arrangement, the attachment bars are in the form of angle bars 20 122 and 122a which have their vertical flanges secured to the inner surfaces of the front and rear frame rails 13, 14.

As previously remarked, the spring assembly 25 may have a full-floating mounting in the frame 11 by connecting both ends of the wire netting to said frame through the medium of tension springs 27. Such an arrangement is illustrated in Figure 4, both ends of the netting being provided with stiffening rods 25 to which the inner ends of 30 the tension springs are connected. Such full-floating mounting disposes the front row of compression springs 18 a greater distance from the front edge of the chair, which makes this embodiment more adaptable to a solid-front chair, 35 but it will be understood that these front springs might be cocked forwardly or otherwise arranged to dispose their upper ends in proximity to the front edge of the chair where it is desired to employ such mounting in a chair having a yield- 40 able front edge.

In lieu of the stiffening rods 25, it may be desirable to employ perforated bars or straps 35 similar to the attachment bars 22, 22a. Such construction is illustrated in Figure 6, each bar 45 35 having a row of closely spaced apertures 36 through which the end strand of the netting is laced. The tension springs 27 may be hooked into intermediately spaced apertures 37, or the apertures 36 may be made sufficiently large to also 50 receive the hook ends of these springs.

While I have illustrated and described what I 55 regard to be the preferred embodiments of my invention, nevertheless it will be understood that such are merely exemplary, and that numerous modifications and rearrangements can be made therein, and that all or certain features of the invention can also be employed in other furniture such as lounges, beds, cots, etc., without departing from the essence of the invention. 60

I claim:

1. A resilient bottom unit for a chair, bed, or the like having a frame, comprising a section of wire netting adapted to be carried by said frame and having interlaced strands including vertically spaced upper and lower strand portions, and a plurality of cushion springs each having their lower convolutions extending between the upper and lower strand portions of a plurality of said strands, the vertical spacing between said upper 65 and lower strand portions being at least equal to the thickness of the wire in said cushion springs, whereby said lower convolutions of the springs can be readily rotated into position between said upper and lower strand portions without requiring 70 75

deformation of said spring convolutions or of said strand portions.

2. A resilient bottom unit for a chair, bed, or the like having a frame, said unit comprising a section of chain-link wire netting adapted to be supported by said frame and including vertically spaced upper and lower strands having interlaced loops, the portions of the loops which interconnect adjacent strands being formed on a curvature of sufficiently large radius to permit relative rolling motion between said loops in either direction at their points of engagement, and a plurality of cushion springs having their lower convolutions extending between and rotatably threaded into position between the upper and lower portions of the loops of adjacent strands and interlocked generally edgewise therewith adjacent said points of relative rolling motion.
- 5 10 15 20 25 30 35 40 45 50 55
3. In a spring cushion for chairs and the like having a frame provided with front and back rails, a length of chain-link wire netting extending between said rails with the strands of said netting extending transversely of said frame and interlaced together to provide axes of relative flexing movement extending transversely of said frame, a rigid attachment bar connected with one of said rails and to one edge of said netting, a rigid stiffening member attached to the other end 35 of the length of netting, tension springs extending generally at right angles to said strands and connected to the opposite rail and to said stiffening member, and upwardly extending coil springs having their lower ends carried by said wire netting, said netting flexing freely about said transverse axes as said tension springs yield when the load transferred by said coil springs to said netting is taken up by said tension springs.
4. In a spring cushion for chairs and the like having a frame provided with front and back rails, a length of chain-link wire netting extending between said rails with the strands of said netting extending transversely of said frame and interlaced together to provide axes of relative flexing movement extending transversely of said frame, a rigid attachment bar connected with one of said rails, the loops of the strand at one edge of said netting receiving said attachment bar, successive loops being formed so that the upper and lower strand portions are spaced apart vertically, the portions of the loops which inter-

connect adjacent strands being formed on a curvature of sufficiently large radius to permit relative rolling motion between said loops in either direction at their points of engagement, a rigid stiffening rod extending through the loops of the strand at the other end of the length of netting, tension springs extending generally at right angles to said strands and connected to the opposite rail and to said stiffening rod, and a plurality of cushion springs having their lower convolutions extending between and rotatably threaded into position between the upper and lower portions of the loops of adjacent strands and interlocked generally edgewise therewith adjacent said points of relative rolling motion.

5 10 15 20 25 30 35

6. In a spring cushion for chairs and the like having a frame provided with rails, a length of chain-link wire netting extending between opposite rails with the strands of said netting extending transversely of the length of the netting and interlaced together to provide axes of relative flexing movement extending transversely of said netting, a rigid attachment bar connected with each of said opposite rails, a rigid stiffening rod at each end of the netting and extending through the loops of the strand at that end, tension springs extending generally at right angles to said strands and connected to each of said attachment bars and to the associated stiffening rods, and upwardly extending coil springs having their lower ends carried by said wire netting, said netting flexing freely about said transverse axes as said tension springs yield when the load transferred by said coil springs to said netting is taken up by said tension springs.

40 45 50 55

6. In a spring cushion for chairs and the like having a frame provided with rails, a length of chain-link wire netting extending between opposite rails with the strands of said netting extending transversely of the length of the netting and interlaced together to provide axes of relative flexing movement extending transversely of said netting, means connecting one margin of said netting to one of said rails, a perforated connecting bar, the opposite margin of said netting having its end strand laced through the perforations in said connecting bar, tension springs extending generally at right angles to said strands and connected to the opposite rail and said connecting bar, and upwardly extending coil springs having their lower ends carried by said wire netting, said netting flexing freely about said transverse axes as said tension springs yield when the load transferred by said coil springs to said netting is taken up by said tension springs.

GUSTAVE P. JOHNSON.
